UNITED STATES PATENT OFFICE.

HAROLD D. PENNEY, OF PELHAM, NEW YORK, ASSIGNOR, BY MESNE ASSIGNMENTS, TO A. G. SPALDING & BROS., OF NEW YORK, N. Y., A CORPORATION OF NEW JERSEY.

GAME FRAME AND METHOD OF MANUFACTURING SAME.

Application filed June 14, 1922. Serial No. 568,343.

This invention relates to striking implements, especially tennis rackets, and to apparatus or processes for making the same though it is noted that the invention is not limited in all respects to these.

One object of the invention is to provide an improved process and construction whereby maximum strength combined with the necessary flexibility and proper weight and balance are imparted to the implement, and a frame provided which is practically indestructible.

Another object of the invention is to provide in a device of this kind improved means and construction whereby balance can be imparted to the racket to suit individual uses.

Another object of the invention is to provide a device of this kind in which the permanent inherent tension of the metal or material used is utilized to maintain the form and elasticity of the implement.

Other objects of the invention are to improve generally the simplicity and efficiency of such devices and processes for making the same and to provide a device of this kind which is durable, and economical to manufacture.

The inventive features for the accomplishment of these and other objects are embodied in an improved racket or implement which, briefly stated, comprises a tubular metallic frame having a body portion and handle portions integral therewith, a center piece between said handle portions, means for securing said piece and handle portions together, and a balancing filler or fillers disposed in said frame to give proper weight and balance to the implement.

Figure 1 is an edge view of a frame for a tennis racket embodying the features of the present invention;

Fig. 2 is a plan view of the completely assembled racket frame;

Figs. 3, 4, 5 and 6 are enlarged transverse sectional views taken respectively, on the lines 3—3, 4—4, 5—5, and 6—6 of Fig. 2;

Fig. 7 is a plan of the formed metal blank

from which the metal portion of the frame is made;

Fig. 8 is a plan showing the metal frame with its wedge or center piece secured therein; the dotted lines showing the initial or natural position of the handle portions of the frame relatively to the center piece before securing them together;

Figs. 9 and 10 are respectively side elevation and transverse section of the metal blank before shaping;

Figs. 11 and 12 are respectively fragmental side elevation and cross-section of said blank with a filler partially inserted.

Fig. 13 is a side elevation of the blank with the filler positioned therein;

Fig. 14 is a plan showing the partially shaped metal blank and the forming block on which it is shaped;

Figs. 15 and 16 are respectively plan and horizontal section of the shaped blank showing different positions of fillers therein; and

Figs. 17 and 18 are respectively transverse sections, on enlarged scales, taken on the lines 17—17 and 18—18 of Figs. 15 and 16 respectively.

Referring to the drawings, A designates generally a tubular frame formed of a light metal such for instance as magnesium or duralumin and bent so as to form a body portion 1 and a pair of leg or handle portions 2, as shown in Fig. 7. The handle portions are provided in their opposing walls with longitudinally extending grooves or channels 3 (Fig. 5), which are deeper at the grip portion of the handle and become shallower as they approach the body until they disappear entirely at the points where the handle merges into the body, as shown in section in Figs. 4, 5 and 6 and in dotted lines in Fig. 2. A center or intermediate piece or wedge 4, formed of wood or any other suitable material is secured between the handle portions 2, and provided at opposite sides thereof with a longitudinally extending rib or tongue shaped to conform with the grooves or corrugation 3 of the handle portions of the frame, said center

piece itself being shaped so as to have an enlarged portion or head 4 and a narrow throat or neck portion 6, whereby when the center piece is placed between the handle portions of the frame and the latter are pressed toward each other they grip the center piece at its throat portion after the manner of a pair of pincers, as indicated in Fig. 8, the handle portions 2, with the center piece between them, being then secured together by means of a number of rivets 7 which pass through transversely registering openings in the frame and center piece.

It has been found that the handle portions 2 of the frame grip the center piece in a permanent manner, and that the tension of the handle portions 2 continues to exert a gripping pressure on the neck portion 6 (without the necessity of screws or the like through the neck portion, as in wooden rackets) even after exposure to weather and atmospheric conditions, or after swelling or shrinkage of the center piece. It is also found that under bad exposure to the weather that the curve of the handle portions 2 where they grip the neck 6 shows no tendency to straighten out as does the similar curve of wooden frames.

In order to impart still greater strength to the frame and particularly to give a finish to the racket, a curved channel or bridge member 8 is provided, which is secured to the body 1 by means of rivets 9, as shown in Fig. 2, the channel thereof receiving the end of the head 5 of the center piece, said head being preferably rabbeted at its opposite sides to receive the side walls of the channel member, so that the outer surfaces of said walls are flush with the surfaces of the center piece, as shown in Fig. 4. It will, of course, be understood that the groove and tongue connection between the center piece and handle portions of the frame may be reversed if desired; that is to say, the grooves may be formed in the center piece and the tongues on the handle portions or other forms of connection may be used. The handle is finished by securing thereto at opposite sides, by means of glue or in any other suitable manner, the usual grip portions 10 for providing the desired hand hold.

The body portion 1 of the frame is provided around its periphery with a line of perforations 11 for the passage of the gut used in stringing the racket, and around its end with a groove 12 for the protection of the gut from injury when the end of the racket strikes the ground.

The racket above described may be made of materials of the proper size, shape and proportion to give the required weight and balance to the racket; but a better way is to have said size, shape and proportions so selected as to give a racket of standard balance and minimum weight and to provide

greater weights and different balances by the addition, during construction, of fillers of wood or other material inserted at the proper parts, or throughout, the tubular frame. Balsa wood, because of its lightness and softness has been found very suitable for this purpose.

One method of inserting the filler is shown in Figs. 9 to 14. In this case a tubular blank 15 of proper size and weight for the lightest weight of racket is selected and into this is inserted a filler 16 of balsa wood or other material which has been previously weighed to give to the completed racket the final required weight. This filler is disposed symmetrically within the blank,—that is, so that its ends 17 are equal distances from the ends of the blank, as in Fig. 13. The blank with the filler therein is then shaped over the forming block 19 (Fig. 14), and the racket 85 then completed in any suitable manner, the holes 11 being drilled in the blank and filler and the grooves 3 and 12 (Fig. 11) being rolled into the blank, after the filler has been inserted and the blank shaped. 90

Should it be found that the method just described, while giving the required balance to the racket, makes the racket too heavy, one or more grooves 20 (Fig. 18) may be previously provided in the filler 16' of 95 sufficient depth to bring the racket to just the required weight.

If it be that balances different from that of Fig. 13 are required, this is easily accomplished by disposing two fillers 16² (Fig. 15) 100 of the required weight and length at that point in the tubular frame that will give the required balance. Or, as in Fig. 16, five fillers 16³ may be disposed at points to give the required balance. 105

The fillers may be of any suitable number and location to give the required balance to suit any condition or individual.

While I have described in detail the structure and process herein illustrated, it is to be understood that I do not thereby limit my invention to the features of construction shown, as I am aware that many mechanical changes and modifications may be made therein without departing from the spirit 110 and scope of the invention as set forth in the claims hereto appended. It will further be understood that while I have described the invention in connection with a tennis racket, the construction is equally applicable 120 to many other implements which must possess a required flexibility, elasticity, lightness and balance combined with strength.

Having thus described my invention, what I claim is:—

1. An implement of the class described, comprising a metallic frame having a body portion and a pair of integral handle forming portions in opposing relation to each other and each having in its inner side a longi- 130

tudinally extending groove merging into a flat surface adjacent to the body portion, an intermediate piece between said handle portions and provided at opposite sides thereof with a longitudinally extending rib adapted to fit into said groove, and means for securing the handle portions and intermediate piece together in such a manner that the metallic frame is under tension.

10 2. A racket comprising a tubular member having an oval portion forming a body portion, inwardly curved portions adjoining the body portion forming a neck, and straight free-ended portions adjoining the inwardly curved portions, and normally diverging from said inwardly curved portions to their free ends and drawn together into substantially parallel relation for forming a handle and exerting tension on the neck, the tubular member being four-sided and the portion of said member forming the body having in cross-section four straight sides and said inwardly curved portions and said free-ended portions having three straight sides and an inwardly grooved side.

30 3. A racket comprising a frame composed of a tubular member forming the body, neck and handle, the tubular member being four-sided and at the body having in cross-section four straight sides and at the neck and handle having in cross-section three straight sides and an inwardly grooved side.

40 4. A racket comprising a tubular member having an oval portion forming a body portion and extended to form a throat portion, a bridge member for the throat portion, inwardly curved portions of the tubular member adjoining the throat portion and forming a neck, normally divergent straight free-ended portions of the tubular member adjoining the neck and drawn together into substantially parallel relation for forming a handle and exercising tension on the neck, a filler between said free-ended portions extending longitudinally thereof, and grips on the handle.

50 5. A racket comprising a tubular member having an oval portion straight-sided in cross-section and forming a body portion and extended to form a throat portion, inwardly curved portions of said member adjoining the throat portion and having in cross-section three straight sides and an inwardly grooved side and forming a neck, a bridge member for the throat portion, normally divergent straight free-ended portions of the tubular member adjoining the neck and having in cross-section three straight sides and an inwardly grooved side and drawn together into substantially parallel relation for forming a handle and exerting tension on the neck, a filler between said free ended portions engaging the inwardly grooved sides and extending longitudinally of said portions, and grips on the handle.

6. A racket comprising a tubular member having an oval portion forming a body portion and extended to form a throat portion, a bridge member for the throat portion, inwardly curved portions of the tubular member adjoining the throat portion and forming a neck, normally divergent straight free-ended portions of the tubular member adjoining the neck and drawn together into substantially parallel relations for forming a handle and exerting tension on the neck and a filler between said free-ended portions extending longitudinally of said portions and into the space between the portions of the tubular member forming the neck and throat and conforming to the shape of said space.

7. A racket formed of resilient tubing and comprising a body portion, a throat portion adjoining the body portion, a neck adjoining the throat portion, and a handle adjoining the neck, the throat portion having space between the portions of the tubing forming the throat portion, and a filler member in said space and conforming to the shape thereof, said handle being formed by normally divergent end portions of the tubing drawn together into substantially parallel relation for forming the handle and exerting tension on the neck and thereby retaining said filler member in the space of the throat portion.

8. A racket formed of resilient tubing comprising a body portion, a throat portion adjoining the body portion, a neck adjoining the throat portion, and a handle adjoining the neck, the throat portion having space between the portions of tubing forming the throat portion and the neck having space between the portions of tubing forming the neck and these spaces communicating with each other, and a filler member in the space of the throat portion and extending into the space of the neck and conforming to the shape of the respective spaces, said handle being formed by normally divergent end portions of the tubing drawn together into substantially parallel relation for forming the handle and exerting tension on the neck and thereby retaining said filler member in the space of the throat portion and neck.

9. A frame for use in construction of striking implements, said frame comprising a metallic tube bent to form a body portion at the mid part of the tube, widely spaced handle portions at the end portion of the tube, and gripping portions between the body portion and the handles and nearer together than the handles.

10. A frame for use in construction of tennis rackets, said frame comprising a tempered elastic light weight metallic tube of substantially square cross-section bent to form a substantially oval body portion at

the mid part of the tube, divergent widely spaced handle portions at the end portions of the tube, and inwardly curved gripping portions between the body portion and the handles.

11. An implement of the class described, comprising a one-piece frame having a body portion merging into a pair of integral handle forming portions; an intermediate piece secured between said handle portions and having a head disposed at the juncture of the handle portions and body; and a metallic bridge member engaging the end of said head and bridging the space at the edge of the head and secured at its opposite ends to said body portion.

12. An implement of the class described, comprising a metallic frame having a body portion merging into a pair of integral handle forming portions; an intermediate piece secured between said handle portions and having a head disposed at the juncture of the handle portions and body; and a curved metallic member of channel formation engaging the end of said head and bridging the space occupied by the head and secured at its opposite ends to said body portion.

13. An implement of the class described, comprising a metallic frame having a body portion, a pair of integral handle forming portions, and inwardly curved gripping portions between the body portion and handles; an intermediate piece disposed between said handle portions and having inwardly curved side faces forming a throat; and means for securing the handle portions and intermediate pieces together in position to cause said handle and gripping portions to clamp the intermediate piece and said throat.

14. An implement of the class described, comprising a metallic frame having a substantially oval body portion and a pair of integral handle forming portions, the inherent elasticity of the frame tending to hold the handle portions spaced apart and diverging from each other toward their free ends; an intermediate piece disposed between said handle portions; and means for securing the handle portions and intermediate piece together in position to cause the elasticity of the frame to cause said handle portions to immovably clamp the intermediate piece.

15. An implement of the class described, comprising a metallic frame having a body portion, a pair of integral handle forming portions and inwardly bent gripping portions between the body portion and handles, the inherent elasticity of the frame tending to hold the handle portions further apart than the gripping portions; an intermediate piece disposed between said gripping portions; and means for securing the handle portions in position to cause the elasticity

of the frame to cause said gripping portions to immovably clamp the intermediate piece.

16. An implement of the class described, comprising a tempered tubular metallic frame having a substantially oval body portion, a pair of integral handle forming portions and inwardly curved gripping portions between the body portion and handles, the inherent elasticity of the frame tending to hold the handle portions spaced apart and diverging from each other toward their free ends; an intermediate piece disposed between said handle portions when the latter are brought into substantial parallelism; and means for securing the handle portions and intermediate piece together in position to cause the elasticity of the frame to cause said handle and gripping portions to immovably clamp the intermediate piece.

17. A racket comprising a resilient metal frame formed of a body portion, opposed handle portions, a tapered member at the inner end of said handle portion, said frame being under tension so as to grip said tapered member.

18. A racket having a resilient metal frame formed of a body portion and opposed handle portions, a wooden member held between said opposed portions, said opposed portions being under such tension as to grip said wooden member.

19. A racket formed of elastic corrugated light metal tubing and a wedge at the inner end of the handle of said racket, and shaped to conform to the corrugation of said tubing, said tubing being under tension so as to grip said wedge.

20. A racket having a frame of resilient tubing, the frame comprising opposed portions of the tubing and a filler member between the opposed portions and conforming to the space therebetween, and normally divergent end portions of the tubing drawn together into substantially parallel relation and thereby exerting tension on the opposed portions of the tubing and retaining said filler member therebetween.

21. A racket having a frame of resilient tubing, the frame comprising opposed portions of the tubing having substantially triangular shaped space therebetween, a wedge member in said space and conforming to the shape thereof, and normally divergent end portions of the tubing drawn together into substantially parallel relation and thereby exerting tension on the opposed portions of the tubing and retaining said member in said space.

22. A racket formed of a metal frame having handle and body portions, the frame prior to stringing being under a tension tending to separate the sides of the body portion.

23. A process for forming a racket which comprises bending a metal tube to form a

substantial oval body portion at the mid part of said tube and divergently spaced handle portions at the end portions of said tube and securing said handle portions to an intermediate member in such a manner that said tube grips said intermediate member by the force of its elasticity.

24. A process of forming a frame for use in construction of a striking implement, said

10 process comprising inserting fillers of soft

wood into predetermined parts of a tempered elastic metallic tube of substantially square cross-section; and then bending said tube to form a substantially oval body portion at the mid part of the tube, and divergently widely spaced handle portions at the end portions of the tube, and securing said handle portions together in such a manner that such frame is held under tension.

HAROLD D. PENNEY.
